UNITED STATES PATENT OFFICE.

THEODORE F. PHILIPPI, OF EAST ST. LOUIS, ILLINOIS.

SWING-FRAME GRINDER.

1,055,075.

Specification of Letters Patent.

Patented Mar. 4, 1913.

Application filed August 23, 1912. Serial No. 716,626.

To all whom it may concern:

Be it known that I, THEODORE F. PHILIPPI, a citizen of the United States of America, and a resident of East St. Louis, county 5 of St. Clair, and State of Illinois, have invented certain new and useful Improvements in Swing-Frame Grinders, of which the following is a full, clear, and exact description, reference being had to the accompanying drawings, forming a part of this specification.

My invention relates to a swing frame grinder and has for its object the production of a grinder carried by a pendant and 15 a counterbalance associated with the pendant so as to allow the grinder to be shifted for a considerable distance with very little labor on the part of the operator.

The invention also includes details of 20 construction which will be hereinafter pointed out.

Figure I is a side elevation of a swing frame grinder embodying the features of my invention. Fig. II is a perspective view 25 showing the pendant suspension and the counterweight.

In the accompanying drawings: A designates a rockable hanger preferably composed of a horizontal beam 1 and hanger 30 rods 2 secured to said beam. The hanger is supported by a hook 3 passing through an eye 4 on the hanger. A pendant B pivoted to the hanger rods is provided with arms 5 having trunnions which extend into 35 the elongated eyes 6 at the lower ends of the hanger rods 2. In operating the grinder the pendant is swung about the axis of the trunnions and these trunnions are free to roll in the elongated eyes 6.

40 A horizontal arm 7, extending from the lower end of the pendant, is pivoted to said pendant at 8 and provided at its free end with a grinding wheel 9. A shaft 10, secured to the grinding wheel is mounted in 45 bearings 8' and provided with a pulley 11. A motor 12 for operating the grinding wheel is carried by the upper end of the pendant.

13 and 14 designate transmission pulleys located at the junction of the pendant B and 50 arm 7. Power is transmitted from the power pulley 15 on the motor to the grinding wheel 9 through the medium of a belt 16 passing around the pulleys 13 and 15, and a second belt 17 passing around the 55 pulleys 11 and 14.

The means for counterbalancing the free end of the arm 7 comprises a lever 18 pivoted to the hanger at 19, a counterweight 20 at one end of said lever and a chain 21 60 connecting the opposite end of said lever to the arm 7.

In the practical use of this apparatus, the operator engages the handles at the free end of the arm 7 and swings the grinding 65 wheel along the surface of the work. A very objectionable feature in the usual types of swing frame grinders is the labor required to swing the arm and pendant. This renders it difficult to operate the 70 grinder and limits the stroke of the swinging frame to a slight distance. Therefore, a very important feature of my invention is that weight at the lower portion of the pendant is counterbalanced by a weight above 75 the pivot of the pendant. This weight is preferably formed by the motor and motor support which lie in a higher plane than the pendant pivot.

I claim:-

80 A swing frame grinder comprising a rockable hanger, a pendant pivoted to said rockable hanger, an arm pivoted to the lower end of said pendant, a grinder carried by said arm, a motor for operating said 85 grinder secured to said pendant, said motor being located in a higher plane than the pendant pivot, a counterbalance lever pivoted to said rockable hanger, and means for connecting said counterbalance lever to said 90 arm.

THEODORE F. PHILIPPI.
